UNITED STATES PATENT OFFICE.

LEONARD GUTEKUNST, OF PHILADELPHIA, PENNSYLVANIA, ASSIGNOR TO THE DE LONG HOOK AND EYE COMPANY, OF PHILADELPHIA, PENNSYLVANIA, A CORPORATION OF PENNSYLVANIA.

HOOK AND EYE.

Application filed June 15, 1926. Serial No. 116,191.

My invention relates broadly to hook and eye structures but more particularly to means for fastening the hook members of such structure to the tape.

5 Various forms of fastening means have been employed heretofore for securing the hooks to the tape, such for instance, as metallic devices of one kind or another. For various reasons these devices have been unsatisfactory, one reason being that the metal employed has been liable to cut through the fabric of the tape and permit separation of the hook therefrom.

The general object of the present invention 15 is to provide an improved and novel construction of metal fastening or anchoring means for securing the hooks of a hook and eye tape structure to the tape constituting one element of said structure.

20 It also is an object of the invention to provide an anchoring device of novel construction including means whereby the prongs or projections thereof which engage the hooks are not liable to cut through the fabric and 25 thereby permit separation of the hook from the tape.

A further object of the invention is to provide a metal fastening means for securing garment hooks to fabric, such as a tape adapted for use as a part of a hook and eye tape structure, in which the said means is provided with a base of relatively large area which is adapted to be located upon the opposite side of the fabric from that on which 35 the hook is located and which is provided with means for engaging the hook at a plurality of points to efficiently and permanently secure said hook to the fabric.

To these and other ends the invention comprehends the construction as hereinafter described in detail, particularly pointed out in the claims and as illustrated in the drawing in which I have shown one form of a convenient embodiment of the said invention. However, it will be understood that the invention is susceptible of embodiment in other forms of construction than that shown and that changes in the details may be made within the scope of the claims without departing from 50 the principle of the invention.

In the drawing:

Fig. 1 is a view in front elevation of a section of hook and eye tape showing a garment hook secured or fastened to the said tape

by metallic fastening means embodying the 55 invention;

Fig. 2 is a view in plan of the opposite side of the said tape section showing the base portion of the said fastening means;

Fig. 3 is a view similar to Fig. 1 except that 60 the bill portion of the hook which is shown in Fig. 1 is cut away so as to expose certain prongs of the fastening means in engagement with the opposite sides of the shank portion of the hook;

Fig. 4 is a sectional view taken on the line 4—4 of Fig. 3;

Fig. 5 is a sectional view taken on the line 5—5 of Fig. 3; and

Fig. 6 is a view in perspective of the fastening means showing certain of the projections thereof which are adapted to be bent to form prongs for engagement with the shank portions of hooks.

Upon reference to the drawing it will be noted that I have shown a section of tape 1 or other fabric upon which is mounted a garment hook 2. The said hook is secured in position by means of a fastening device of novel construction embodying my invention. The said

fastening device comprises a sheet of metal of T-shape including the stem portion 3 and a cross-wise extending portion 4. At its outer end the stem is provided with projections 5 which extend in opposite directions as shown 85 in Fig. 6 which are adapted to be bent upwardly, as best indicated in Figs. 4 and 5, in which position they are adapted to be inserted through the fabric 1. The width of the stem portion 3 is substantially the same 90 as the width of the shank portion of the garment hook with which the bent-over ends 7 of the prongs 5 are adapted to engage. It

will be noted that the T-shaped fastening device is located upon the opposite side of the fabric 1 from that on which the hook 2 is located. The cross-wise extending portion 4 of the fastening device is provided with tubular projections 10 which are adapted to project through the fabric 1 and also through 100 the fastening eyes 11 of the hook. Having been inserted through the fabric and through the eyes these tubular projections are upset in known manner, as indicated at 12. It will

be seen, therefore, that the hook is secured 105 to the fabric not only at the extreme outer or rear end of the shank but also at the forward end of the said shank at points adjacent

the bend between the shank and bill portions of the hook.

It will be apparent from an inspection of the drawing that the area of the fastening device comprising the parts 3 and 4 is quite considerable or extensive, in consequence of which when the tubular rivet portions 10 and the prongs 5 are inserted through the fabric and engaged with the hook the said fabric is not liable to be cut by any part of the fastening means, nor is the fabric liable to be accidentally disconnected from the fastening means. The result, therefore, is that the hooks, when fastened upon a fabric such as one of the tape members of a hook and eye tape structure, are not liable to become accidentally disconnected from the said tape. Tape structures of the character referred to are employed for many purposes, but one of the principle uses thereof is as a fastening means for openings of brassières, corsets and the like. It is important, therefore, that the fastening means for securing the hooks in place shall be of a character to permanently and securely hold the hooks to the tapes so that there shall not be the annoyance which would arise from the frequent detaching of a hook from the tape, whether while in use or at some other time, as when the garment is being laundered.

Having thus described my invention, what I claim and desire to secure by Letters Patent is:

1. In a hook and eye tape structure, means for fastening garment hooks to tape including a metallic member having a surface extent, substantially equal to that of the shank portions of the hooks, which member is pro-

vided with projections which are adapted to engage the fastening eyes of a garment hook, and also having means adjacent its opposite end for engaging the shank portions of the said hooks.

2. Means for fastening garment hooks to textile fabric, which comprises a metal plate member of T-shape and of an area substantially equal to that of the shanks of the hooks, the cross-wise portion of the said member being provided with tubular projections, and the stem portion of said member being provided with prongs, the said projections and prongs being adapted to pass through the said fabric and to engage the said garment hooks upon opposite sides of the said fabric.

3. A hook tape, comprising metallic fastening means for securing the hooks on said tape, each of said fastening means comprising a sheet metal member of T-shape, the cross-wise extending portion of said member having hollow tubular projections extending at right angles to the plane of said member, and the outer end of the stem of said T-shaped member having projections at the opposite edges thereof, the said tubular projections and the projections at the outer end of the stem of the said member being adapted to project through the said tape and to engage a hook member of a hook and eye fastening device at the outer end of the shank portion thereof and at points adjacent the bend between the shank and bill portions respectively, substantially as described.

In testimony that I claim the foregoing as my invention I have hereunto signed my name this 11th day of June, A. D., 1926.

LEONARD GUTEKUNST.
